UNITED STATES PATENT OFFICE.

EDGAR M. CAIN, OF WILMINGTON, DELAWARE.

RAILWAY-SIGNAL.

No. 888,959.

Specification of Letters Patent.

Patented May 26, 1908.

Application filed January 17, 1908. Serial No. 411,328.

To all whom it may concern:

Be it known that I, EDGAR M. CAIN, a citizen of the United States, residing at Wilmington, in the county of Newcastle and State of Delaware, have invented new and useful Improvements in Railway-Signals, of which the following is a specification.

This invention relates to railway signals, the object in view being to provide an audible signal arranged at the side of the railway bed and adapted to be set in operation by a moving train while the train is passing a point three hundred yards from a red signal, sounding the whistle thirty seconds and thereby calling attention of the engineer, brakeman and others on the train of the fact that danger is ahead. The signal hereinafter described is especially valuable in foggy weather and at night in the event of the signal light getting out of order.

With the above general object in view, the invention consists in the novel construction, combination and arrangement of parts as herein fully described, illustrated and claimed. In the accompanying drawings:—Figure 1 is a perspective view of a portion of a railway, showing a signal stand and some of the connections forming part of the present invention. Fig. 2 is an enlarged elevation of the upper portion of the stand, showing the whistles, valves, valve operating magnets, etc. Fig. 3 is an enlarged detail sectional view of the two way valve which controls one of the whistles. Fig. 4 is a plan view of the same. Fig. 5 is a detail view of one of the magnets showing also a portion of the arm of one of the two-way valves. Fig. 6 is a detail vertical section showing the circuit closer and the means for operating the same. Fig. 7 is a sectional plan view of the same.

Referring to the drawings, 1 designates a signal stand arranged at one side of a railway and equipped with the ordinary signals 2 adapted to be operated by compressed air 45 which is led thereto by a compressed air pipe 3 indicated by dotted lines in Fig. 1, the main compressed air pipe line 3 having a branch 4 which extends upward within the stand 1.

Mounted upon the stand 1 is a plurality of tanks 6 and under the preferred embodiment of this invention, one of said tanks is used for each track and a whistle 7 is provided for each tank. These whistles have distinguish-

ing sounds to designate the respective tracks 55 to which they refer. The branch pipe 4 which extends upward within the stand 1 is connected at a suitable point with a horizontal branch 8 and this branch 8 is in turn branched as shown at 9, said branches 9 being in communication with the whistles 7 and tanks 6 and being controlled by a two-way valve, as shown at 10. In carrying out this feature of the invention, the pipe 9 is provided with a T-coupling or valve casing 11 in 65 which the valve 10 is rotatably mounted, said valve having the stem 12 thereof extended outward beyond the casing and an operating lever arm 13 being mounted fast on said stem. The stem 12 has a spring 14 70 coiled around the same with one end of the spring secured to the valve casing, as shown at 15 and the other end engaging over the lever arm 12 as shown at 16, the tension of said spring being exerted to hold the lever arm 13 75 in a substantially horizontal position as shown in Fig. 2 and also acting to restore the arm to a horizontal position after it has been elevated by the armature 17 and electro magnet 18 mounted on a bracket 19 secured 80 to the stand.

The pipe 20 leads from the valve casing 11 into the adjacent compressed air tank 6 and the passage 21 of the valve is so cored out that when the arm 13 occupies a horizontal 85 position, the compressed air delivered by the pipe 9 passes through the valve and the connection 20 into the tank. When the arm 13 is drawn upward by the action of the electro magnet 18, the pipe 9 is closed below the valve 90 casing and the air then passes from the tank 6 through the connection 20 and valve passage 21 and upward to the whistle 7 thereby sounding the whistle and at the same time cutting off the supply of air to the tank 6. 95

In order to throw the electro magnet 18 into circuit and energize said magnet, I provide a train operated circuit closer shown in Fig. 6 consisting of a box 22, mounted underneath one of the track rails and having a depressible cap or cover 23 adapted to be depressed by the wheels of the cars irrespective of the direction in which the train is moving. The box 22 is recessed in its upper edge and a rubber gasket 24 in the form of a ring is seated in said recess, the lid or cover 23 resting on said gasket and admitting of a limited amount of depression or downward movement of the

lid or cover for a purpose which will appear, said gasket also serving by its resiliency to again elevate the lid 23 when stress is removed therefrom.

5 The lid 23 is provided with a projection 25 which bears against the underside of a flexible plate 26 which directly underlies one of the track rails, the latter being indicated by dotted lines in Fig. 6 at 27. The tie, just 10 under the plate 26 is hollowed or dished somewhat as indicated by dotted lines at 28 to admit of the downward movement or depression of the plate 26 under the weight of the train in passing over the rail 27.

15 To the underside of the lid 23 is secured a metal plate 29 which is insulated from the lid as shown and provided with a contact point 30 which when depressed is adapted to rest against another contact point 31 in the form 20 of a pin carried by a metal plate 32 mounted on a yielding support 33 and insulated therefrom as shown in Fig. 6. The support 33 is mounted upon and upheld at a certain elevation by means of an underlying spring 34, the 25 contact points 30 and 31 being normally out of contact. The support 34 is provided with oppositely extending wings 35 which are movable up and down between parallel guides 36. These guides are provided with 30 bases 37 by which they are secured in the bottom of the box 22 and the upper ends of said guides are provided with bridge pieces or cutting bars 38 through which are inserted adjusting screws 39 by means of which the 35 height of the contact points 31 may be nicely adjusted. Wires 40 and 41 lead off from the plates 29 and 32 to the proper electro magnet 18 hereinabove described, it being understood that a battery or generator of any suitable description is interposed in the circuit 40 formed by the wires 40 and 41.

The lid or cover 23 is also capable of a slight adjustment which is accomplished by hinging said cover at one side of the box as 45 shown at 42 and providing an adjusting screw 43 at the opposite side of the box, as clearly shown in Fig. 6 so that by tightening or loosening the nut 44 of the clamping screw the lid may be correspondingly lowered 50 or raised to adapt the same to the position of the plate 26 under the superimposed rail.

The moment the cap or cover 23 is depressed the electrical circuit is closed, the proper magnet is energized, the valve 10 55 shifted and air is applied by the tank 6 to the appropriate whistle 7. This whistle sounds thirty seconds while the train is passing at a point where the signaling apparatus is located, thus notifying the train's crew of 60 danger. As soon as the train passes the apparatus, the compressed air tank is immediately re-charged in readiness for the next train.

Having thus fully described the invention, what is claimed as new is:—

1. A railway signal embodying a compressed air tank, means for introducing air into said tank, a whistle in communication with the tank, a valve controlling the communication between the tank and whistle, an electro-magnet for operating said valve, and a train operated circuit closer in the same circuit with said magnet, substantially as described.

2. A railway signal embodying a compressed air tank, a whistle, a compressed air pipe leading to the whistle and tank, a two-way valve controlling the passage of air to the whistle and tank and from the tank to the whistle, an electro-magnet for operating said valve, and a train operated circuit closer adapted to be operated by a moving train and embodying contact points arranged in the same electrical circuit with the magnet, substantially as described.

3. A railway signal embodying a whistle, an air tank, a compressed air pipe communicating with the whistle and tank, a valve controlling the admission of air to the tank and also controlling the passage of air from the tank to the whistle, an electro-magnet for operating said valve, and a train operated circuit closer in the same electrical circuit with said magnet and embodying means operated by the depression of a rail for setting the circuit closer, substantially as described.

4. A railway signal embodying an air reservoir, a whistle, an electro-magnet for throwing said whistle connected therewith into operation, and a circuit closer embodying yielding contact points in the same electrical circuit with the said magnet, one of said contact points being associated with and moved by an unsupported portion of one of the track rails.

5. A railway signal embodying an air reservoir, a whistle connected therewith, an electro-magnet for throwing said whistle into operation, and a circuit closer embodying a box arranged beneath the roadbed and adapted to be acted upon by a yielding rail, a movable lid or cover for said box, a terminal contact point carried by said lid, another contact point yieldingly supported in the box, means for adjusting the position of the last named contact point, and an electrical circuit in which said contact points and the electro-magnet are included.

In testimony whereof I affix my signature in presence of two witnesses.

EDGAR M. CAIN.
